ATTORNEY

UNITED STATES PATENT OFFICE

JOHN F. GRACE, OF ARLINGTON, NEW JERSEY, ASSIGNOR TO WORTHINGTON PUMP AND MACHINERY CORPORATION, OF NEW YORK, N. Y., A CORPORATION OF VIRGINIA

CONDENSER

Application filed March 8, 1928., Serial No. 260,019.

This invention relates to steam condensers of the surface type and the primary object of the invention is to provide a condenser in which the cooling water, which is not treated for purification, is circulated through the tubes of the condenser, and its mixing with and contamination of boiler feed water which is, in present pure water power plant systems treated to eliminate to the greatest possible extent corrosion and other detrimental action on the boiler tubes and other mechanism employed in the power plant, will be prevented.

To overcome such leakage, it is necessary to provide fluid tight connections between the tubes and the heads of the condenser, and in so doing, cognizance must be taken of and compensation made for variances in the temperatures in the condenser, and variances in the expansion and contraction relation of the tubes with the shell or casing of the condenser.

It is an object of the present invention to provide a simple, efficient and relatively inexpensive condenser construction which will permit fluid tight connections between the tubes and tube heads, allowing movement of one of the tube heads relative to the casing to compensate for expansion and contraction of the tubes under variances of temperatures in the condenser.

The present invention embodies a condenser having a tube sheet into which the ends of the condenser tube are expanded, movably mounted and connected to the condenser shell by a gasket or fluid tight expansion joint and one which includes suitable supporting means for relieving the expansion joint of the stress of the weight of the moveable parts of the condenser and of the tubes which are connected to the tube sheet without interfering with the movement of the tube head under the expansion and contraction of the tubes.

With these objects in view, the invention consists in various features of construction and combination of parts, which will be first described in connection with the accompanying drawings, showing a condenser of the preferred form embodying the invention, and

the features forming the invention will be specifically pointed out in the claims.

In the drawings:

Fig. 1 is a side elevation partly in section of a condenser showing one embodiment of the present invention.

Fig. 2 is an end elevation of the condenser.

Referring more particularly to the drawings, the condenser comprises a shell 1 in which is located suitable tube heads, one of which is shown at 2, it being understood that the other tube head is mounted within the condenser shell in the approved conventional manner. The exhaust steam to be condensed enters the condenser through the exhaust inlet 3 and passes therethrough, transversely of the tubes 4 while the condensate is delivered to a suitable hot well (not shown,) from which it is drawn off in the usual manner. The tubes 4 have their ends expanded into the tube sheets to provide fluid tight joints and prevent the leakage of cooling water which is circulated through the tubes in the usual approved manner for condensing the steam.

In the form illustrated, the tube sheet 2 is connected to the water box 10 as clearly shown at 11 in Fig. 1 of the drawings, and the tube sheet 2 and water box 10 are connected to the condenser shell 1 by a flexible gasket 12 which may be formed of rubber, a composition of rubber and fabric or any suitable material found practicable for the purpose and which is not subject to ready corrosion and deterioration by the action of the water and steam thereon.

The tube sheet 2 and water box 10, being connected to the condenser casing 1 by the expansion joint 12 are movable relative to the condenser casing upon expansion and contraction of the tubes 4 so as to compensate for such expansion and contraction and prevent rupturing of the connection between the tubes and the tube sheets.

Owing to the relatively great weight of the tube sheet 2, the adjacent portions of the tubes which are attached thereto and the water box 10, moveable supporting means is provided for supporting the water box independently of the expansion joint 12 and to

relieve the expansion joint of the stresses due to the weights of the parts above mentioned. In the forms shown in Figs. 1 and 2 of the drawings, rollers 14 are provided which are connected to the drawings 10 by a bracket or brackets 15 and these rollers move over a suitable supporting surface as indicated at 16 so as to provide supported movement of the tube sheet 2 and water box 10.

From the foregoing description taken in connection with the drawings, it will be noted that moveable means either in the form of the tube sheet alone or of the tube sheet and the water box are provided for compensating for the expansion and contraction of the tubes and that these moveable means are supported for movement by suitable rollers.

It will be understood that the invention is not to be limited to the specific construction or arrangement of parts shown but that these may be modified widely within the invention defined by the claims.

What is claimed is:

1. In a condenser, a shell, a tube sheet, a water box, tubes having fluid tight connection with said tube sheet, an expansion joint between said tube sheet and water box and said shell to permit movement of the tube sheet and water box relative to the shell, and supporting rollers carried by said water box for supporting the water box and tube sheet independently of said shell.

2. In a condenser, a shell, a tube sheet, a water box, a flexible fluid tight connection between the tube sheet and shell, a bracket attached to the outside of the water box and a roller carried by said bracket to permit supported movement of the water box and tube sheet independently of said shell.

3. In a condenser, a shell, a water box, a tube sheet, tubes having fluid tight connection with said tube sheet, an expansion joint between the tube sheet and shell, a bracket carried by said water box, a rotatable roller carried by said bracket to permit supported movement of the water box and tube sheet.

4. In a condenser, the combination with a support independent of the condenser, of a shell, a water box, a tube sheet, an expansion joint, said tube sheet and water box connected to said shell by said expansion joint, and means carried by said water box and engaging said support to permit supported movement of said water box and tube sheet.

5. In a condenser, the combination with a support independent of the condenser, of a shell, a water box, a tube sheet, an expansion joint, said tube sheet and water box connected to said shell by said expansion joint, and a roller carried by said water box and engaging said support to permit supported movement of said water box and tube sheet.

In testimony whereof I affix my signature.

JOHN F. GRACE.
